UNITED STATES PATENT OFFICE.

ARNOLD NACKE, OF PHILADELPHIA, PENNSYLVANIA, ASSIGNOR TO LEDIG & HERRLEIN, OF SAME PLACE.

DESIGN FOR A WALL-STAND.

SPECIFICATION forming part of Design No. 17,064, dated January 11, 1887.

Application filed November 1, 1886. Serial No. 217,736. Term of patent 3½ years.

To all whom it may concern:

Be it known that I, ARNOLD NACKE, a citizen of the United States, residing in the city and county of Philadelphia, State of Pennsylvania, have invented and produced a new and original Design for Wall-Stands, of which the following is a specification, reference being had to the accompanying photographic illustration, forming part thereof.

10 The leading features of my design for a wall-stand are, first, side sections of triangular form and a central section of quadrilateral form surmounting the same, and, next, side sections surmounted by a central section, and shelves intermediate of the side sections.

15 A B represent side sections of a skeleton wall-stand, the same consisting of a series of shelves, C C, and columns D. The said shelves C are rounded on the front outer edge, as shown in the drawing, and the upper one of each section has a cornice above the same. Extending from one side section to the other are shelves E E, on the same plane as the lower shelves, C C. The side sections are surmounted 20 by a central section, F, which consists of a top shelf, G, and columns H, the latter rising from the side sections, C C. The columns D, which are arranged in a triangular form in each section, are quadrangular in shape throughout 25 their length and continuous of the legs J of the stand.

K represents scrolls extending from the shelf G to the columns H. Knobs L rise from the topshelf of the shelves of the side sections, and also from the shelf G of the central section. 35 The several shelves are edged with pendants.

I claim—

1. A design for the skeleton wall-stand herein shown and described, the same consisting of the central quadrangular group of uprights or standards, having upon each outer side thereof a single upright set within the vertical plane passing through the two rear uprights, and having a series of shelves with rounded extremities horizontally disposed 40 within the said uprights.

2. A design for the skeleton wall-stand herein shown and described, the same consisting of the central quadrangular group of uprights or standards, having upon each outer side thereof a single upright set within the vertical plane passing through the two rear uprights, and having a series of shelves with rounded extremities horizontally disposed 45 within the said uprights, and surmounted by 50 a section having its extremities above the vertical projection of the quadrangular group of standards.

ARNOLD NACKE.
